UNITED STATES PATENT OFFICE.

WILLIAM F. PARKER, OF NEW YORK, N. Y.

DESIGN FOR A CORNER STRIP OR PLATE.

SPECIFICATION forming part of Design No. 30,775, dated May 16, 1899.

Application filed April 19, 1899. Serial No. 713,692. Term of patent 14 years.

To all whom it may concern:

Be it known that I, WILLIAM F. PARKER, a citizen of the United States, residing at New York, in the county of New York and State of New York, have invented and produced a new and original Design for Corner Plates or Strips; and I do hereby declare the following to be a full, clear, and exact description of the same, reference being had to the accompanying specification and drawings, forming a part thereof.

My invention consists in a new and original design for corner plates or strips used in the construction of buildings for protecting the angles or corners of plastered walls.

The invention is illustrated in the accompanying drawings, in which—

Figure 1 is a perspective view of a corner strip or plate made according to my design. Fig. 2 is a transverse sectional view of the same, taken on the line $x x$.

The leading feature of my design consists in an angularly-bent plate or strip that is provided throughout its length with a series of vertically-disposed elongated slots or recesses and a series of oblique or inclined slots or recesses.

Referring to the drawings, the reference-numeral 1 designates the body of the strip or

plate, which is bent over at the point 2 and 30 doubled or folded upon itself to provide two thicknesses of metal the faces of which lie in close contact and the edge 3 of the folded-over portion terminating and lying close to and parallel with the edge 4 of the body of 35 the strip. This folded or doubled strip or plate is bent throughout its length along the line 5, so that one portion thereof will extend outward at an oblique angle from the other, and this outwardly-extending portion 40 is provided throughout its length with a series of elongated vertically-disposed slots or openings 6, which extend entirely through the same, while the body or opposite portion of the strip or plate is provided throughout its 45 length with a series of inclined or obliquely-arranged elongated slots or openings 7, which extend entirely therethrough.

What I claim is—

The design for a corner strip or plate, substantially as shown and described.

In testimony whereof I affix my signature in presence of two witnesses.

WILLIAM F. PARKER.
